CARRIER HANDLE

Alfred Anderson, Chicago, Ill.

Application January 9, 1930. Serial No. 419,715

4 Claims. (Cl. 299—112)

This invention relates in general to carrier handles, but more particularly it has reference to improvements in double leather handle carriers which provide a strong and durable handle of 5 long lasting qualities which is more particularly adapted to be used with fire hose equipment.

An important object of this invention is to provide for re-inforcing the leather portion of a handle throughout its entire length, and between 10 metal connector plates.

Another important object of this invention is to provide a simple means for substantially connecting a pair of my improved handles to connecting links or ring fittings, whereby to provide 15 a double handle carrier more particularly adapted for use with fire hose equipment.

Another important object of this invention is to provide the ends of the re-inforced leather portion of the handle with metal connector ends or 20 caps to provide a strong metal connection for a handle to links or ring fittings which provide connection for two handles to provide a double handle carrier which is more particularly adapted for use with fire hose equipment.

25 A further important object of my improvement contemplates the provision of single and double metal connector ends or caps which may be easily detachably secured over the ends of the re-inforced leather portion of a handle, and which 30 may be readily connected to links or ring fittings which provide connection for a pair of handles having the above stated characteristics.

A still further object of my improvement contemplates the provision of a double handle carrier 35 which not only has the above stated qualifications but which also provides a simple and neat appearing strong double handled carrier handle which will stand a great deal of hard usage, and which may be produced at, comparatively, a very 40 small cost.

These and other objects of my improvements embodied in my invention will be better understood by referring to the accompanying drawing, and will be more fully described in the following specification, and more particularly 45 pointed out in the appended claims.

In the drawing, Figure 1 is a side view of a double handle carrier embodying the improvements as contained in my invention, and shows it installed on a portion of a fire hose nozzle which is shown in light dotted lines;

Fig. 2 is a view taken from the plane 2—2 of Fig. 1, and shows the manner in which one end 50 of my double handle carrier is connected to a ring

fitting which fits around the outer end of a portion of a fire hose nozzle;

Fig. 3 is a view taken from the plane 3—3 of Fig. 1, and shows the manner in which the opposite end of said carrier is connected to a ring 60 fitting which fits around the inner end of a part of a fire hose nozzle;

Fig. 4 is a sectional view taken on the plane 4—4, of Fig. 3;

Fig. 5 is a sectional view taken on the plane 5—5 of Fig. 2; the rivets and re-inforcing bar not being shown in section;

Fig. 6 is a sectional view taken on the plane 6—6 of Fig. 3; the rivets and re-inforcing bar not being shown in section. 70

Similar characters refer to similar parts throughout the several views.

This invention contemplates a double handle carrier which, as before stated, is particularly adapted for use with fire hose equipment and 75 comprises a metal re-inforced leather handle portion 9, provided with a re-inforcing member 10, the ends of both said leather portion 9, and said member 10, terminating between portions of end connectors or caps, 11 and 12, respectively, 80 and there fastened by means of rivets 13, as is shown in Figures 1, 2, 3, 4, 5, and 6.

The upper connector 11, comprises but a single bifurcated piece, while the lower connector 12, is composed of two, substantially similar halves, 12'. 85

Ring fittings or links 14 and 15 are provided for making connection between a pair of handles to form a double handle carrier, indicated generally, in Fig. 1, as "H". Upper ring 14, as is being provided on fire hose nozzles of the character shown 90 is provided with two pairs of outwardly extending opposite lugs 14'; each pair of lugs being provided with opposite openings, one of which being tapped, and through which a screw threaded connection pin, 16, is inserted. 95

Upper connector 11, is provided with an opening 17, extending crosswise thereof, and through which, said pin 16, is inserted when making connection between ring 14, and handle connector 11. 100

Lower ring 15, as is being provided on fire hose nozzles of the character shown has two pairs of opposite outwardly extending lugs 18, extending therefrom; each pair of lugs being connected to each other at their ends by an integral round bar 19; said bar 19, providing means by which to 105 make connection between ring 15 and handle connector 12.

Lower connector 12, is especially made in two similar halves, 12', the halves having a flat surface 20, which join each other when assembled; 110

said flat surface being grooved, as at 21, transversely of connector 12, to fit over said bar 19. Screw holes 22, are provided in connector 12, into which screws 22' are fastened when assembling ring 15, and handle connector 12, together.

In making up a handle "H", strips of leather are selected and arranged to enclose a metal reinforcing bar 10, by being seamed together with stitching 9', on each side of said bar throughout its entire length. A strong metal connector is provided for each end of said portion, 9, with which to make a strong and durable connection to ring fittings, 14 and 15, which are adapted to fit over a part of a fire hose nozzle "N", and, at the same time, form a connection between a pair of re-inforced leather handles to provide a double handle carrier "H".

When it is desired to replace a worn out leather handle portion 9, it will be only necessary to remove rivets 13, and pull said handle 9, from said connectors, 11 and 12, and then insert a new one and fasten it in place by riveting as before.

To overcome the troublesome and expensive feature of having to renew handles often, I have, as before stated, provided the ends of a re-inforced leather handle, with strong and substantial metal connectors, such as have been previously described, which provide hose nozzle carrying handles which will be very economical, in that they will stand up against hard usage for a long period of time.

Having thus described my invention, it can be readily understood that the minor details of my construction may be altered in various ways without departing from the spirit and scope of my invention, therefore, what is claimed is desired to be secured by Letters Patent.

I claim:

1. The combination in a substantially non-breakable carrier handle, of the character described, of a U-shaped reinforced non-breakable leather handle, a pair of connecting links adapted to fit over a fire hose nozzle, and comparatively broad bifurcated metallic handle connectors rigidly secured over the ends of said handle, and

means for forming a substantial non-twistable connection of the said handle connectors to said links, substantially for the purpose specified.

2. A carrier handle, of the character described, comprising a leather encased strong flat-like metallic reinforcement bar bent to form a U-shaped handle and having one of its broad surfaces formed convex and the opposite surface thereto flat, comparatively broad bifurcated metallic handle connectors arranged over the ends of said bar and the casing therefor and there fastened as by means of rivets, and a pair of connecting links adapted to fit over a fire hose nozzle; said connectors being arranged and secured to form substantial non-twistable connections with said links whereby to form a double handled carrier, substantially as described.

3. The combination in a substantially non-breakable carrier handle, of the character described, of a U-shaped reinforced non-breakable leather handle, a pair of connecting links adapted to fit over a fire hose nozzle, a comparatively broad one piece bifurcated connector for one end of said handle, a substantially identical pair of comparatively broad connector pieces for the other or opposite end of said handle, said pair of pieces being adapted to form a bifurcated connector similar to that of said one piece connector, and means on said links and said connectors providing means for making a substantial non-twistable connection between the handle and said links, substantially as described and for the purpose specified.

4. A double handled carrier comprising a pair of oppositely disposed U-shaped reinforced leather handles, a bifurcated metallic connector rigidly secured on each end of said handles, and a pair of connecting links comprising ring fittings for a fire hose nozzle and means for making connections between said handles; the said connectors being arranged and secured to form a rigid and non-twistable connection between said handles and the said links.
